RAT GUARD

Ean Lee Bush, San Francisco, Calif.

Application August 29, 1947, Serial No. 771,201

5 Claims. (Cl. 114—221)

1

This invention relates to rat guards.

An object of this invention is to provide a rat guard which is light, can be easily handled and easily clamped upon a hawser, whether it is a single or double hawser, and which will effectively prevent the passing of rats or insects along the hawser.

I am aware that some changes may be made in the general arrangements of the several devices and parts, as well as in the details of the construction thereof without departing from the scope of the present invention as set forth in the following specification, and as defined in the following claims; hence I do not limit my invention to the exact arrangements and combinations of the said device and parts as described in the said specification, nor do I confine myself to the exact details of the construction of the said parts as illustrated in the accompanying drawings.

With the foregoing and other objects in view, which will be made manifest in the following detailed description, reference is had to the accompanying drawings for the illustrative embodiment of the invention, wherein:

Fig. 1 is a perspective view of a rat guard constructed in accordance with my invention in place upon a hawser.

Fig. 2 is a face view of the rat guard in the open position.

Fig. 3 is a sectional view of the rat guard the section being taken on the lines 3—3 of Fig. 2.

Fig. 4 is a fragmental face view of the rat guard in closed position clamped over a double hawser.

Fig. 5 is a fragmental view of the outer periphery of the rat guard showing the securing handle partly in section.

Fig. 6 is a sectional view of the rat guard the section being taken on the lines 6—6 of Fig. 4.

In carrying out my invention I make use of a circular disc or plate 1. A substantially radial slot 2 extends from the periphery of the plate 1 substantially to its center and is offset at the inner end thereof to form a socket 3 with a semi-circular closing edge 4 generally fitting over the usual hawser 6. The offset corners 7 of the slot 2 are curved also substantially at the same radius as that of the closing edge 4.

On a portion of one face of the plate 1 is superimposed a sector plate 8 substantially corresponding to about one-half of the area of the first plate 1 and having an outer periphery concentric with the outer periphery of the plate 1. The two plates are pivoted together on a pivot 9 central to the first plate 1. The socket 3 for the hawser is offset to one side of the pivot 9 or of the center of the plate 1, oppositely from the sector plate 8.

The outer edge of the sector plate 8 is bent over upon itself to form an arcuate channel 11 which slidably fits over the outer edge of the circular plate 1. This channel 11 extends from the trail-

2

ing edge 12 of the sector plate 8 to a point 13 spaced from the leading edge 14 of said sector plate. The leading edge of the sector plate is substantially parallel with the adjacent edge of the slot 2 from the outer periphery to about the offset corner 7 of the slot 2 at which point the leading edge 14 is curved into a socket 16 complementary to the closed edge 4 of the first socket 3 for effectively surrounding and clamping the hawser 6 therebetween. It is to be also noted that the edges 12 and 14 of the sector plate are flanged outwardly away from the first plate 1. The edge of the socket 3 of the plate 1 is also flanged outwardly at the portion thereof near the pivot 9.

On the end of the pivot 9 farthest from the sector plate is pivoted the inner end of a bar 17 which is curved near the pivot at the same radius and substantially parallel with the complementary socket 16 of the leading edge 14 of the sector plate 8 and which bar 17 then extends parallel with the leading edge 14 of the sector plate 8 to the outer periphery of the sector plate 8 and beyond the unflanged portion of this periphery outside of the end 13 of the channel 11. On the outer end of this bar 17 is provided a handle 18 secured to the sector plate 8. On this handle 18 is pivoted a handle clamp 21 at its end nearest to the periphery of the plate 1, on a pivot 22 as shown in Fig. 5. A spring 23 bent into substantially a U-shape, has one leg secured in a detent 24 on the handle clamp 21 so that its other end 26 bears against the handle 18 and normally urges the handle clamp 21 around its pivot 22 towards the outer periphery of the plate 1. The inner edge 27 of the handle clamp 21 is slanted toward the outer periphery of the plate 1 so as to be held in a strong frictional engagement therewith by the spring 23. By pressing upon the handle 18 and the handle clamp 21 the spring 23 is compressed and the handle clamp 21 is released from the periphery of the plate 1 and allows the shifting of the sector plate 8 along the face of the plate 1 so as to be moved over the slot 2 into hawser clamping position as shown in Figs. 1 and 4, or back into the open position as shown in Fig. 2. Upon the release of the handle 18 and of the handle clamp 21, the inner edge 27 is engaged with the edge of the plate 1 and frictionally holds the sector plate 8 in the adjusted position.

On the face of the plate 1 adjacent the bar 17 is provided a ridge 28 which protrudes toward the bar 17. This ridge 28 extends substantially parallel with the edge of the slot 2 farthest from the leading edge 14 of the sector plate 8 in the open position, and extends substantially parallel with the offset socket 3 and around to the pivot 9. As soon as the bar 17 passes over the outer end of the slot 2 it engages the outer portion of the ridge

28 thereby accomplishing a tight engagement between the bar 17, the plate 1 and the sector plate 8. The clamping handle on the outer end of the bar 17, in effect, straddles the outer edge of the plate 1 so that by gripping the same the bar 17 and the sector plate 8 are manipulated together to closing or opening positions.

The pivot 9 is tubular and through the hole 29 thereof extends a line 31, with a knot 32 at its outer end, the other end of which line 31 in turn can be held either on an object ashore or on the hawser 6 so as to prevent the dropping of the rat guard into the water when it is released from the hawser 6. Due to the unbalanced arrangement of the channel 1 as well as the bar 14 with respect to the slot 2, when the rat guard of my construction is dropped into position on the hawser 6 it assumes a position with the slot 2 pointing downwardly by reason of the location of the center of gravity of the unit downward from the center 9. The offset socket 3 by its eccentric arrangement permits a firmer clamping and encircling of the hawser and adapts the rat guard to be used with efficiency either on a single hawser as shown in Fig. 1 or on a two line hawser shown in Fig. 4, or any multiple hawser. The unit can be made of light sheet material yet be a firm and positive rat guard; it can be handled easily both for clamping and releasing; it does not require any adjustments or fastening means in position, and it is eminently adapted for its purposes.

I claim:

1. In a rat guard of the character described a substantially circular plate having a radial slot extended from its outer periphery toward the center, said slot having at its inner end an offset extension to one side and beyond the center of said plate to form an eccentric socket, a sector plate superimposed on one side of said plate being concentric with said first plate and being pivotally secured to the center of said first plate and being adapted to hold a hawser in said socket, an element along the other face of said first plate being pivoted on said center, and a releasable clamping handle connecting said sector plate and said element for manipulating the shifting of said sector plate and said element over said slot for engaging a hawser in said socket.

2. In a rat guard of the character described a substantially circular plate having a radial slot extended from its outer periphery toward the center, said slot having its inner end formed into a socket, a sector plate superimposed on one side of said plate being concentric with said first plate and being adapted to hold a hawser in said socket, an element along the other face of said first plate being pivoted on said center and movable with said sector plate, a releasable clamping handle on said sector plate for manipulating the shifting of said sector plate and element over said slot for engaging a hawser in said socket, and a ridge on the first plate around said socket protruding toward said element and being on the side of said slot farthest from said element in the open position of said sector plate for tightly pressing against said element and drawing said sector plate against the other side of said first plate.

3. In a rat guard of the character described a substantially circular plate having a radial slot extended from its outer periphery toward the center, said slot having at its inner end an offset extension to one side and beyond the center of said plate to form an eccentric socket, a sector

plate superimposed on one side of said plate being concentric with said first plate and being pivotally secured to the center of said first plate and being adapted to hold a hawser in said socket, an element along the other face of said first plate being pivoted on said center, and a releasable clamping handle connecting said sector plate and said element for manipulating the shifting of said sector plate and said element over said slot for engaging a hawser in said socket, a ridge on the first plate substantially parallel with an edge of the slot and around said socket protruding toward said element and being on the side of said slot farthest from said element in the open position of said sector plate for tightly pressing against said element and drawing said sector plate against the other side of said first plate, said guide engagement being an interlocking peripheral channel coacting with said ridge for tightening said plates together.

4. In a rat guard of the character described a substantially circular plate having a radial slot extended from its outer periphery toward the center, said slot having at its inner end an offset extension to one side and beyond the center of said plate to form an eccentric socket, a sector plate superimposed on one side of said plate being concentric with said first plate and being pivotally secured to the center of said first plate and being adapted to hold a hawser in said socket, an element along the other side of said first plate being pivoted on said center and being movable with said sector plate, a releasable clamping handle on said sector plate for manipulating the shifting of said sector plate over said slot for engaging a hawser in said socket, the edge of said sector plate adjacent said slot being curved near said pivot to complement said socket when opposite the same, said element being curved near the pivot parallel with said curved edge for complementing said socket.

5. In a rat guard of the character described a substantially circular plate having a radial slot extended from its outer periphery toward the center, said slot having at its inner end an offset extension to one side and beyond the center of said plate to form an eccentric socket, a sector plate superimposed on one side of said plate being concentric with said first plate and being pivotally secured to the center of said first plate and being adapted to hold a hawser in said socket, a tubular pivot for pivoting said plates together through the center of the first plate, a holding line extended through said tubular pivot, and means on one side of said pivot to hold said line therein.
